(57) **CLAIM**

The ornamental design for a nozzle, as shown and described.

DESCRIPTION

FIG. 1 is a rear perspective view of a nozzle showing my new design;

FIG. 2 is a front perspective view thereof;

FIG. 3 is a top view thereof;

FIG. 4 is a right side elevation view thereof, the left side elevation being a mirror image thereof;

FIG. 5 is a bottom view thereof;

FIG. 6 is a rear edge view thereof; and,

FIG. 7 is a front edge view thereof.

The broken lines are for purposes of illustration and form no part of the claimed design.
